UNITED STATES PATENT OFFICE.

MICHAEL LIPTAK, OF ST. PAUL, MINNESOTA.

FURNACE WALL.

Application filed August 3, 1925. Serial No. 47,818.

To all whom it may concern:

Be it known that I, MICHAEL LIPTAK, a citizen of the United States, residing at St. Paul, in the county of Ramsey and State of Minnesota, have invented certain new and useful Improvements in Furnace Walls; and I do hereby declare the following to be a full, clear, and exact description of the invention, such as will enable others skilled in the art to which it appertains to make and use the same.

My present invention relates particularly to walls for furnaces and to that type of furnace wall that comprises what may be designated as a permanent wall and a replaceable wall, the two walls being connected by blocks or elements that extend from the one wall into the other and are so arranged that partial replacements of the inner wall may be made without disturbing undamaged portions thereof. Generally stated, the invention consists of the novel devices, combinations of devices and arrangement of parts hereinafter described and defined in the claims.

In the accompanying drawings, which illustrate the invention, like characters indicate like parts throughout the several views.

Referring to the drawings:

Fig. 1 is a fragmentary perspective showing a wall structure designed in accordance with my invention, some parts thereof being removed;

Fig. 2 is a plan view of the wall shown in Fig. 1;

Fig. 3 is a section taken approximately on the line 3—3 of Fig. 2, some parts being removed and some parts being broken away;

Figs. 4, 5 and 6 are perspectives showing the several specially constructed blocks used in the wall illustrated in Figs. 1, 2, and 3;

Figs. 7 and 8 are fragmentary plan views illustrating slightly modified forms of the wall illustrated in Figs. 1, 2 and 3;

Fig. 9 is a vertical section taken approximately on the line 9—9 of Fig. 8, some parts being removed and some parts being broken away;

Fig. 10 is a fragmentary perspective showing the type of structure illustrated in Figs. 1, 2 and 3 incorporated in a central or partition wall of the furnace, some parts being removed;

Fig. 11 is a plan view of the wall shown in Fig. 10;

Figs. 12 and 13 are perspectives showing in detail the specially constructed blocks used in the wall shown in Figs. 10 and 11; and

Fig. 14 is a view corresponding to Fig. 11, but illustrating a slightly modified arrangement.

The permanent wall, which in the wall structure illustrated in Figs. 1, 2 and 3 is the outer wall, may be made up entirely of fire brick or in part of fire brick and in part of common brick, and it includes horizontal belts 15 of such bricks laid in the usual or any suitable way; and between these belts, said permanent wall includes specially constructed blocks 16 advisably made of fire clay. These blocks 16 are substantially L-shaped, but are formed on oblique lines so that when they are laid together as shown in Fig. 2, they extend obliquely across the joints of the bricks of the belts 15 and leave oblique recesses that are open at the inner face of the permanent wall. This oblique arrangement, as will presently appear, is highly important. Moreover, it is important that the blocks 16 of the adjacent vertically spaced courses are reversed so that they extend reversely oblique, that is, the one at an acute angle to the wall faced toward the left and the other at an acute angle toward the right.

The replaceable or inner wall is made up of horizontal belts 17 of fire brick, preferably laid as headers, and interposed horizontal layers of specially constructed fire bricks or blocks 18 and 19. The blocks 18 and 19 are in the form of oblique parallelograms, that is, they have parallel sides but the ends thereof are obliquely formed. The relatively long bricks or blocks 18 are adapted to be inserted into the oblique recesses formed between the oblique portions of the blocks 16 of the outer wall, and when thus inserted, they project into the replaceable wall between the fire brick belts 17. As shown, said blocks 18 are of such length that they extend to the inner face of the replaceable wall. The blocks or bricks 19 extend only through the replaceable wall and fill the spaces between the relatively long blocks 18. The blocks 18 of the one row are extended obliquely in one direction and the blocks of the adjacent vertically spaced rows are oblique in the other direction. These blocks and the bricks of the belts 17 will become fused together more or less under

the action of the intense heat from the furnace, and when thus fused, will be very securely united so that the reversely oblique blocks 18 produce a sort of dove-tailed bond between the permanent and replaceable walls. The long blocks 18 are extended such distance into the recesses of the outer or permanent wall that they will support the brick belts 17 and permit replacements of portions thereof without disturbing overlying or adjacent belts. This fact is clearly illustrated in Fig. 1.

When the blocks and bricks of the replaceable or inner wall have been burned away to a serious extent and require replacement, the shortened blocks 18 may be removed and new blocks substituted therefor; and to facilitate this removal, said blocks 18 are preferably provided with indentations 18^a that are adapted to be engaged by a hammer *a*, as shown in Fig. 3. In Fig. 3, the dotted lines *b* indicate the portions of the blocks and bricks that have been burned away back to the broken lines *c*.

In the wall described, the block elements 16 and 18 are the largest and heaviest in the wall and even these are of such comparatively light weight that a mason can easily lift and place the same with one hand. Moreover, these blocks and all of the blocks and bricks of the wall are of very simple construction and may be cheaply made and will not be easily broken in handling. Hence, the block-forming elements may be manufactured at low cost and the wall may be built therefrom at a minimum of expense. Moreover, the wall thus constructed may be of very high efficiency, both as to durability and facility for repair.

The wall illustrated in Fig. 7 is like that illustrated in Figs. 1, 2 and 3, except that the L-shaped blocks 16^a are formed with longer outer wings, so that the blocks 18 are placed in pairs within the recesses formed in the permanent wall by the said blocks 16^a.

The wall illustrated in Figs. 8 and 9 is like that illustrated in Figs. 1, 2 and 3 except that the permanent wall, instead of being made of two horizontal courses of bricks, is made of three horizontal courses 15^a, and the L-shaped blocks 16^b are formed with wider outer wings than the blocks 16, so that the blocks 19 may be used between the blocks 18.

As already noted, Figs. 10 to 14, inclusive, illustrate the invention incorporated in a central or partition wall of a furnace and, hence, comprises a permanent central wall and replaceable walls on each side thereof. In this wall structure, as illustrated in Figs. 10 to 13, inclusive, the permanent or central wall is made up of horizontal belts of brick 20, preferably of the fire brick, and oblique laterally spaced blocks 21 also of fire clay or

tile. These blocks 21 in form are oblique parallelograms of such length that they extend flush with the two faces of the permanent central wall. Said blocks 21 are spaced so that they afford oblique recesses 70 extending therebetween and through the central wall.

The replaceable walls are formed from belts 22 of fire brick, preferably laid as headers, and horizontal rows of laterally spaced relatively long blocks 23, which in form are also oblique parallelograms. These blocks 23, when inserted into the recesses formed in the central wall between the spacing blocks 21, meet at the central portion 80 of the center wall with their outer oblique ends flush with the exposed surfaces of the respective replaceable walls. The said blocks 23, when applied as described and shown in the drawings; will support the brick belts 22 so that they may be replaced in whole or in part without disturbing overlying or underlying belts. To facilitate removal of the blocks 23 that have been burned away, they are shown as provided with indentations 23^a. To fill the spaces in the replaceable walls left between the blocks 23, shorter blocks 24 are provided; and these blocks 24 in form are also oblique parallelograms and they should be made of fire clay or tile.

The wall shown in Fig. 14 is like that illustrated in Figs. 10 and 13, except that the long blocks 23 are located in pairs and the spacing blocks 21 are spaced farther apart, so as to receive the said pairs of blocks between them. Obviously, this center or partition wall structure has all the advantages enumerated or which are found in the outside wall structure illustrated in Figs. 1, 2 and 3.

The scheme above disclosed is capable of modification within the broad scope of the invention. The blocks or bricks in the form of oblique parallelograms are desirable because they give a smooth surface to the inner face of the replaceable wall, but rectangular bricks or blocks having square corners but obliquely exposed to the wall may be used with this slight disadvantage, however, that if they extended to the inner surface of the wall, they would produce a somewhat irregular surface. Rectangular blocks or bricks such as just noted may be found for sale on the market and carried in stock by most brick manufacturing concerns.

It is further important to note that the blocks 18, 19, 21, 23 and 24 are alike at both ends and hence are reversible end for end so if one end happens to be slightly broken or notched in shipment or handling, the bad end can be placed inward and the better or more perfect end outward. Moreover, the blocks are of such form that they are not likely to be broken in shipment.

What I claim is:

1. A wall structure including a permanent wall and a replaceable wall, said replaceable wall including obliquely set blocks or bricks extended into the permanent wall and seated therein.
2. A wall structure including a permanent wall and a replaceable wall, said replaceable wall including obliquely set blocks or bricks extended into the permanent wall and seated therein, the said oblique blocks or bricks being some obliquely arranged in one direction and others obliquely in another direction, so as to obtain a dovetail anchorage between the permanent and replaceable walls.
3. A wall structure including a permanent wall and a replaceable wall, said replaceable wall including obliquely set blocks or bricks extended into the permanent wall and seated therein, the said oblique blocks or bricks being arranged in horizontal rows and the said replaceable wall including brick belts filling the spaces between said horizontal rows of oblique blocks, the bricks of said belts being laid with joints perpendicular to the inner face of the wall structure.
4. A wall structure including a permanent wall and a replaceable wall, said replaceable wall including obliquely set blocks or bricks extended into the permanent wall and seated therein, the said oblique blocks or bricks being some obliquely arranged in one direction and others obliquely in another direction, so as to obtain a dovetail anchorage between the permanent and replaceable walls, the said oblique blocks being arranged in horizontal rows and the said replaceable wall including brick belts filling the spaces between said horizontal rows of oblique blocks, the bricks of said belts being laid with joints perpendicular to the inner face of the wall structure.
5. A wall structure including a permanent wall and a replaceable wall, said replaceable wall including obliquely set blocks or bricks extended into the permanent wall and seated therein, the said oblique blocks or bricks in form being oblique parallelograms.
6. The structure defined in claim 2 in which said oblique blocks or bricks in form are oblique parallelograms.
7. A wall structure including a permanent wall and a replaceable wall, said replaceable wall including obliquely set blocks or bricks extended into the permanent wall and seated therein, the said oblique blocks or bricks being horizontally spaced, and relatively short oblique filler blocks or bricks in the spaces between said oblique blocks or bricks.
8. A wall structure including a permanent wall and a replaceable wall, said replaceable wall including obliquely set blocks or bricks extended into the permanent wall and seated therein, the said oblique blocks or bricks being some obliquely arranged in one direction and others obliquely in another direction, so as to obtain a dovetail anchorage between the permanent and replaceable walls, the said oblique blocks or bricks being horizontally spaced, and relatively short oblique filler blocks or bricks in the spaces between said oblique blocks or bricks.
9. A wall structure including a permanent wall and a replaceable wall, said replaceable wall including obliquely set blocks or bricks extended into the permanent wall and seated therein, the said replaceable wall including horizontal belts of bricks interposed between horizontal vertically spaced rows of said obliquely set blocks or bricks.
10. The structure defined in claim 2 in which said replaceable wall also includes horizontal belts of bricks laid as headers and at approximately right angles to the face of the wall.
11. The structure defined in claim 4 in which the bricks of the belts of said replaceable wall are laid as headers and approximately at right angles to the face of the wall.
12. A wall structure including a permanent wall and a replaceable wall, said replaceable wall including obliquely set blocks or bricks extended into the permanent wall and seated therein, the said oblique blocks or bricks having recesses at their intermediate portions for facilitating the removal thereof.

In testimony whereof I affix my signature.

MICHAEL LIPTAK.
